COIN COLLECTOR

John F. House, Miami, Fla.

Application October 17, 1933, Serial No. 694,002

11 Claims. (Cl. 194—2)

The present invention relates to new and useful improvements in coin collectors particularly for use in public vehicles, theaters, etc. and has for its primary object to provide, in a manner as hereinafter set forth, a device of this character embodying a novel construction, combination and arrangement of parts through the medium of which the correct amount of money will be retained and the correct change returned regardless of the denominations of the coins which are inserted or the sum thereof up to a predetermined maximum above the correct amount.

Another very important object of the invention is to provide a coin collecting device of the aforementioned character which may be conveniently regulated or adjusted to retain various amounts of money and return the correct change should the sum of the coins inserted exceed the desired amount.

Another important object of the invention is to provide a coin collector of the character set forth embodying a register which automatically totals the sums of money retained.

Still another important object of the invention is to provide a coin collecting device of the character described including a signal which functions when the correct amount of money or more than the correct amount has been inserted.

A still further important object of the invention is to provide a coin collector which comprises novel change delivering mechanism or means.

Other objects of the invention are to provide a coin collector which will be comparatively simple in construction, strong, durable, highly efficient and reliable in operation, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a coin collector constructed in accordance with the present invention.

Figure 2 is a view in side elevation thereof.

Figure 3 is a top plan view.

Figure 4 is a view in rear elevation of the device with a portion of the housing removed to expose the mechanism.

Figure 5 is a view in front elevation with a

portion of the housing removed to expose the mechanism.

Figure 6 is a view in top plan with a portion of the housing removed to expose the mechanism.

Figure 7 is a view in horizontal section through a portion of the invention, taken substantially on the line 7—7 of Figure 5.

Figure 8 is a vertical sectional view through a portion of the device, taken substantially on the line 8—8 of Figure 5.

Figure 9 is a vertical sectional view through a portion of the device, taken substantially on the line 9—9 of Figure 5.

Figure 10 is a detail view in side elevation of the coin receiving unit, looking at the same from the inner side thereof.

Figure 11 is a detail view in vertical longitudinal section through the coin receiving unit.

Figure 12 is a detail view in vertical longitudinal section showing the main shaft and the elements mounted thereon, etc.

Figure 13 is a detail view principally in vertical section through the change regulating shaft and the associated elements.

Figure 14 is a detail view in vertical section through the change delivering unit.

Figure 15 is a detail view in front elevation of the adjustable, numbered dial.

Figure 16 is a detail view in perspective of one of the levers constituting a part of the change delivering mechanism.

Figure 17 is a detailed view in vertical section, taken substantially on the line 17—17 of Figure 16.

Figure 18 is a detail view in perspective of one of the cam actuated rocker arms constituting a part of the change delivering mechanism.

Figure 19 is a detail view in front elevation of the segmental gears which are selectively engaged with that portion of the invention shown in Figure 12 for actuating the same.

Figures 20, 21 and 22 are detail views in vertical transverse section, taken substantially on the lines 20—20, 21—21 and 22—22, respectively, of Figure 19.

Figure 23 is a detail view in end elevation of the segmental gear unit shown in Figure 19.

Figure 26 is a detail view in side elevation of the coin actuated switch control bar.

Figures 27 and 28 are detail views in side elevation of the segmental driven and driving gears, respectively.

Figure 29 is a detail view in front elevation of the cam unit which actuates the change returning elements.

Figures 30, 31, 32 and 33 are detail views in vertical transverse section taken substantially on the lines 30—30, 31—31, 32—32 and 33—33, respectively, of Figure 29.

Figure 34 is a detail view in elevation, looking at one end of the unit shown in Figure 29.

Figure 35 is a detail view in side elevation of the left hand end portion of the unit shown in Figure 29.

Figure 36 is a detail view in perspective of the member which opens the safety switch and throws out the dogs which are shown in detail in Figure 37.

Figure 37 is a detail view in perspective of the dogs which normally retain the mechanism shown in Figure 12 against retrograde rotation.

Figure 38 is a detail view in front elevation of the clutch operating arm and its shaft.

Figure 39 is a vertical sectional view, taken substantially on the line 39—39 of Figure 6.

Figure 40 is a detail view in front elevation of the segmental gear which drives the register.

Figure 41 is a detail view in front elevation of the unitary ratchet and gear which are driven by the segmental gears shown in Figure 19.

Figure 42 is a detail view in top plan of one of the change delivering slides or ejectors.

Figure 43 is a detail view in elevation of the spring which normally maintains the segmental gear shown in Figure 40 in operative position.

Referring in detail to the drawings, it will be seen that the embodiment of the invention which has been illustrated comprises a housing which is designated generally by the reference numeral 1, said housing including an elevated bottom or floor 2 beneath which an electric motor 3 is suspended. An endless belt 4 connects the motor 3 with a comparatively large drive pulley 5 which is loosely mounted on the reduced outer end portion 6 of a shaft 7 which is journaled in the housing 1. Fixed on the shaft 7 is a worm gear 8. Slidably mounted on the shaft 7 and keyed thereto is a clutch 9 which operatively connects the shaft 7 with the pulley 5 for actuation thereby, the adjacent face of said pulley having pins 10 thereon with which the clutch is engageable. A spring 11 yieldingly urges the pulley 5 away from the clutch 9.

The clutch 9 is shifted through the medium of a yoke 12 which is fixed on a rocker shaft 13 journaled between posts 14 which rise from the bottom 2 of the housing 1. Depending from the rocker shaft 13 is an arm 15 to which the lower end of a swinging, suspended armature 16 is connected by a link 17. The armature 16 is attracted by an electro-magnet which is mounted on the bottom 2 of the housing 1. When the electro-magnet 18 is energized, the clutch 9 is shifted into engagement with the pulley 5 for driving the gear 8 on the shaft 7. A pull spring 19 is connected to the yoke 12 for disengaging the clutch 9 when the electro-magnet 18 is deenergized.

Journaled in the housing 1, above the shaft 7 and transversely relative thereto, is a shaft 20 having fixed on an intermediate portion thereof a worm gear 21 which is engaged with the gear

8. Fixed on the forward end portion of the shaft 20 is a disk 22 on the rear or inner face of which a segmental beveled gear 23 is fixed. Journaled in an upper portion of the housing 1, and extending at right angles to the shaft 20, is a shaft 24 which is intermittently driven through the medium of a segmental beveled gear 25 fixed on one end thereof, said gear 25 being operatively engaged with the segmental gear 23. The gear 25 is brought to a stop and releasably secured in a predetermined position through the medium of a pivoted arm 26 having a pin 27 thereon which is engageable in a socket provided therefor in one face of said gear 25. The arm 26 is yieldingly urged toward the gear 25 by a spring 28.

As illustrated to advantage in Figures 5, 10 and 12 of the drawings, a coin receiving unit designated generally by the reference numeral 29 is mounted in the upper forward portion of the housing 1. The coin receiving unit 29 includes an elongated horizontal casing 30 having a longitudinally extending chamber 31 therein with which a longitudinal slot 32 in the inner side of said casing 30 communicates. Also communicating with the chamber 31 is a coin inlet opening 33 in the top of the casing 30 and a coin discharge opening 34 in the bottom of said casing, said openings 33 and 34 being at longitudinally spaced points in the casing.

Slidable in the chamber 31 of the unit 29 is a follower 35 which is connected by a pin 36 to one end of a pitman 37 which, in turn, is operatively connected to the disk 22, said pin 36 being operable in the slot 32 of the casing 30. Operable in the chamber 31 of the casing 30 is a slide 39 having one end formed to provide steps 40 with which coins of various denominations which are inserted are engageable. The coins which are inserted through the inlet opening 33 are moved forwardly by the follower or pusher 35 until they drop through the discharge opening 34, during which movement said coins connect the slide 39 to said follower or pusher for actuation thereby. It may be well to here mention that in Figures 10 and 11 of the drawings, the follower 35 is not shown in fully retracted position. Anti-friction rollers 41 are mounted in the upper portion of the casing 30 with which the slide 39 is engaged.

As best seen in Figure 25 of the drawings, the slide 39 has formed thereon a lateral wing 42 which is also operable in the slot 32 of the casing 30. Projecting inwardly from the free longitudinal edge of the wing 42 is a finger 43, the purpose of which will be presently set forth. The wing 42 has formed therein a series of openings 44, the purpose of which also will be presently set forth. Projecting laterally from the outer face of the slide 39 is a cam 45 which is operable in a longitudinal slot 46 (see Figure 5) which is provided therefor in the forward or outer side of the casing 30. Extending from one end of the cam 45 is an extension 47 to which a spring 48 is connected, said spring 48 constituting means for returning the slide 39 to retracted or inoperative position.

Mounted adjacent one end portion of the casing 30 of the unit 29 is a switch which is designated generally by the reference numeral 49 which controls the flow of current to the electric motor 3 and the electro-magnet 18. The switch 49 includes a plate 50 which is mounted for vertical and rocking movement in the chamber 31 through the medium of a pin 51 (see Figure 75

11) which extends through the lower portion of said plate, said pin 51 being operable in vertical slots 52 which are provided therefor in the walls of the casing 30. The pin 51 projects beyond the front wall of the casing 30 for a purpose which will be presently set forth. Secured on the outer or forward side of the plate 50 is a block 53 of insulating material which is operable in an opening 54 (see Figure 5) which is provided therefor in the outer or front wall of the casing 30 and which has mounted thereon a contact 55 to which, of course, a conductor wire is connected. The contact 55 is engageable with a resilient contact 56 which is mounted on an insulating block 57 on the front wall of the casing 30. At its upper end, the plate 50 terminates substantially in a point and said plate is yieldingly urged upwardly and rearwardly in the chamber 31 by a spring 58 engaged with the lower end thereof. The arrangement is such that the spring 58, in addition to yieldingly urging the plate 50 upwardly, also rocks said plate 50 in a direction to disengage the contacts 55 and 56.

Mounted for longitudinal sliding movement in the casing 30 above the plate 50 is a coin retracted bar 59 which extends into the opening 33 for engagement and actuation by the coins as they are inserted. The bar 59 is supported at one end by a roller 60. At an intermediate point, the lower edge of the bar 59 has formed therein a recess which provides a shoulder 61 which is engageable with the substantially pointed free upper end of the plate 50. Projecting from one side of the rear end portion of the bar 59 is a pin 62 which is operable in a slot 63 (see Figure 5) provided therefor in the forward wall of the casing 30 and to which a spring 64 is connected for yieldingly urging said bar 59 forwardly at all times. Movement of the bar 59 under impulsion by the spring 64 is limited by the engagement of the pin 62 with the forward end wall of the slot 63, as will be apparent. It may be well to here mention that swinging movement of the plate 50 under impulsion by the spring 58 is limited by the engagement of the insulating block 53 with the rear wall of the opening 54, as suggested in Figure 5 of the drawings. The recess in the bar 59 which forms the shoulder 61 accommodates the upper end portion of the plate 50 when said bar 59 is shifted to retracted position against the tension of the spring 58 by a coin which is being inserted.

Referring now to Figure 10 of the drawings, it will be seen that the reference numeral 65 designates a lever which is pivotally mounted, as at 66, on the inner or rear side of one end portion of the casing 30. At its free end, the lever 65 terminates in a cam 67. Fixed on an intermediate portion of the lever 65 is a dog 68 which is engageable in the openings 44 of the wing 42. A spring 69 yieldingly urges the lever 65 downwardly. Mounted for swinging movement in a vertical plane on the casing 30 is an angular lever 70 which is actuated in one direction by the pin 36. The angular lever 70 is pivotally mounted on the casing 30 at one end, as at 71, and said lever is provided with a slot 72 in its other end portion which accommodates a headed guide pin 73. Pivotal mounted on the angular lever 70 is a pawl 74 which is operatively engageable with a ratchet wheel 75 which is rotatably mounted on the casing 30 for actuating said ratchet wheel in a step by step fashion. The reference numeral 76 designates a substantially

U-shaped spring which is secured, as at 77, on the casing 30, one end of said spring being engaged with the pawl 74 for maintaining said pawl in engagement with the ratchet wheel 75, the other end of the spring being engaged with the angular lever 70 for returning said angular lever to retracted or inoperative position. The teeth of the ratchet wheel 75 constitute cams which are engageable with the adjacent end portion of the pin 51 for moving the plate 50 downwardly in the chamber 31 against the tension of the spring 58. The lever 65 is swung upwardly against the tension of the spring 69 by engagement of the pin 36 with the cam 67 when the follower 35 returns to retracted or inoperative position.

As illustrated to advantage in Figure 13 of the drawings, a sleeve 78 is splined on the shaft 24, said sleeve constituting the hub portion of a series of segmental gears 79, 80, 81 and 82 which, as shown by Figures 22 to 33, inclusive, are provided with various numbers of teeth. The sleeve 78 has formed therein an annular channel 83 in which the finger 43 which projects from the wing 42 is engaged for connecting said sleeve to the slide 39 for actuation thereby. Also mounted on the shaft 24 is a fixed sleeve 84 having a longitudinal rib 85 thereon constituting a cam the purpose of which will be hereinafter set forth. The end of the sleeve 78 which is adjacent the fixed sleeve 84 has formed thereon a cam 86 (see Figure 6), the purpose of which will also be presently set forth.

Mounted in the housing 1 in spaced parallelism beneath the shaft 24 is a normally stationary but manually rotatable shaft 87 having one end slidably keyed or pinned in a longitudinal socket 88 provided therefor in a comparatively short shaft 89 which extends slidably through the adjacent side wall of the housing 1. Fixed on the outer end of the shaft 89 is an operating knob 90. The inner end portion of the shaft 89 is enlarged and has formed integrally therewith a disk 91 and a sprocket gear 92, said disk 91 having openings 93 therein in which a pin 94 which projects inwardly from the adjacent side wall of the housing 1 is selectively engageable for retaining said disk in adjusted position. As best seen in Figure 9 of the drawings, pins 95 are also provided on the adjacent side wall of the housing 1 for engagement with stop lugs 96 on the periphery of the disk 91 for limiting rotation of said disk in opposite directions.

Loosely mounted on the outer end portion of the shaft 87 is a segmental gear 97 which is engaged with the adjacent end of the shaft 89 by a forked spring 98. It will thus be seen that the spring 98 functions in a manner to force the shaft 89 outwardly for engaging the pin 94 in one of the openings 93 of the disk 91.

Rotatably mounted on the shaft 87 is a drum 99 which is secured against longitudinal movement on said shaft through the medium of a pin 100 which is engaged in a groove 101 which is provided therefor in the shaft. Integral with one end of the drum 99 is a gear 102 and integral with the other end of said drum is a ratchet wheel 103. Pins 104 project longitudinally from one end of the drum 99, said pins being slidably engaged in sockets 105 which are provided therefor in the adjacent segmental gear 97 for connecting said gear to the drum for actuation thereby.

Loosely mounted on the inner portion of the

shaft 87 is a sleeve 106 having cams 107 and a ratchet wheel 108 integral therewith. Mounted between the sleeve 106 and the drum 99 is a spacing collar 109 which is secured in position by a transverse pin 110. The projecting end portion of the pin 110 is engageable with a pin 111 which projects from the gear 102. The pin 111 is engageable with a pin 112 which projects from a cam 113 on the adjacent end of the sleeve 106. This is shown to advantage in Figures 12 and 39 of the drawings.

As also shown to advantage in Figure 39, a cable 114 has one end secured to the drum 99 for winding thereon and its other end connected to a drum 115 which is rotatably mounted on a support 116 for winding thereon. The drum 115 is automatically actuated in a direction to wind the cable 114 thereon by a spring 117. It will thus be seen that when the gear 102 is rotated sufficiently by one of the segmental gears on the shaft 24, the pin 111 will engage the pin 112 for rotating the sleeve 106, thereby setting the cams 107. The distance the cams 107 are rotated depends upon the distance that the pins 111 and 112 are normally spaced from each other, which distance is regulated as desired by forcing the shaft 89 inwardly against the tension of the spring 98 and then manually rotating said shaft which, of course, rotates the gear 102. The spring drum 115 rotates the drum 99 with the gear 102 thereon in the opposite direction until arrested by the engagement of the pin 111 with the pin 110. It will be noted that the shaft 87 in which the pin 94 is mounted is stationary when the pin 94 is engaged in one of the openings 93 of the disk 91.

The reference numeral 118 (see Figure 37) designates a shaft which is journaled in the lower portion of the housing 1 adjacent the shaft 87 and in parallelism therewith. Fixed on the shaft 118 is a pawl 119 which is operatively engaged with the ratchet wheel 103 on the drum 99. Also fixed on the shaft 118 is an arm 120 having a projection 121 on its free end portion which rides on the periphery of the cam 113 on the end of the sleeve 106. Said cam 113 is provided with a recess or notch 122 in its periphery for the reception of the projection 121. Thus, when the cam 113 is rotated with the sleeve 106, the projection 121 rides out of the recess 122, thereby rocking the shaft 118 in a manner to disengage the pawl 119 from the ratchet wheel 103 for permitting the spring drum 115 to return the gear 102 to its former position. A spring 123 (see Figure 6) is engaged with the arm 120 for yieldingly urging said arm toward the cam 113 and the pawl 119 into engagement with the ratchet wheel 103. A finger 124 depends from one end portion of the shaft 118 for a purpose 60 to be presently set forth.

The sleeve 106 with the cams 107 thereon is returned to its normal position, or reset, through the medium of a cable 125 (see Figure 6) which is connected at one end to said sleeve and which is windable thereon. The other end of the cable 125 is connected to a spring actuated drum 126 for winding thereon, said drum 126 being similar to the drum 115. The sleeve 106 is releasably secured against actuation by the drum 126 by a pivoted, spring actuated dog 127 having a pin 128 rising therefrom in the path of the cam 86 (see Figure 6) for engagement and actuation to inoperative position by said cam 86.

Referring now to Figures 1, 2, 3 and 14 of the drawings, it will be seen that a change return-

ing unit designated generally by the reference numeral 129 is mounted on the front wall of the housing 1. The unit 129 comprises a frame structure which includes a top 130, a bottom 131 which projects forwardly beyond the top 130, and uprights 132. Extending between the top and bottom 130 and 131 is a series of tubular coin magazines 133 which, of course, accommodate coins of various denominations. The top 130 is provided with openings for loading the magazines 133, said openings being closed by a hinged closure 134 which may, if desired, be locked in closed position by any suitable means. The bottom 131 has formed therein slideways 135 in which coin ejectors 136 are mounted for reciprocation. Communicating with the slideways 135 are upper and lower openings 137 and 138, respectively, the latter being forwardly offset relative to the former. The openings 137 communicate with the magazines 133 for the passage of the coins. The ejectors 136 are provided with openings 139 which receive the coins from the openings 137 and convey said coins to the openings 138 through which said coins drop by gravity into a hopper 140 which depends from the bottom 131.

Depending from the hopper 140 is a delivery tube 141 upon which a manually operable sleeve 142 is slidably mounted. The bottom of the hopper 140 is normally closed by a hinged closure 143 to which a rearwardly and downwardly extending arm 144 is fixed. The arm 144 is operable in a vertical slot 145 in the delivery tube 141 and is engaged in an opening 146 in the sleeve 142. Thus, when the sleeve 142 is elevated the closure 143 is swung downwardly to open position for permitting the discharge of the coins from the hopper 140. When the sleeve 142 is released, said sleeve returns by gravity to inoperative position thereby swinging the closure 143 upwardly to closed position, the downward movement of the sleeve being arrested by the engagement of the arm 144 with the lower end wall of the slot 145.

The reference numeral 147 designates springs 45 which are secured at one end, as at 148, to the rear portion of the top 130. The free ends of the springs 147 are engaged between upstanding flanges 149 on the rear end portions of the ejectors 136 for returning said ejectors to retracted position.

Now, referring to Figures 7 and 8 of the drawings, it will be seen that the reference numeral 150 designates a horizontal shaft adjacent the cams 107 upon which a plurality of vertical levers 151 are pivotally mounted at an intermediate point for swinging movement in a vertical plane, said levers corresponding in number to the cams 107. Pivotally mounted at an intermediate point on the upper ends of the levers 151 are rocker arms 152 having one end portion engaged on the cams 107, said one end portion of the rocker arms being formed to provide shoulders 153 for engagement by the cam 85 on the shaft 24. Springs 154 are mounted on the levers 151 and engaged with the rear ends of the rocker arms 152 for yieldingly maintaining said rocker arms in engagement with the cams 107.

Mounted for horizontal sliding movement in 70 the housing 1, adjacent the bottom 2 of said housing, are plunger rods 155 which are coupled, at an intermediate point, to the lower end portions of the levers 151 by pin and slot connections 156. The plunger rods 155 are engageable, 75

at their forward ends, with the rear ends of the ejectors 136 for shifting said ejectors against the tension of the springs 147. Coil springs 157 are provided for returning the plunger rods 155 to retracted position.

5 Rotatably mounted in the upper rear portion of the housing 1 is a dial 158 having numerals 159 on its face. The upper portion of the dial 158 is operable in an extension 160 which rises from the top of the housing 1, said extension 160 having a window 161 in its forward side through which the numerals 159 may be observed. Of course, but one of the numerals 159 10 at a time can be seen through the window 161. As best seen in Figure 6 of the drawings, a beveled gear 162 is fixed centrally on the rear of the dial 158 and said gear 162 is meshed with a beveled gear 163 which is fixed on an intermediate portion of a horizontal shaft 164 15 which is journaled in the upper rear portion of the housing 1. The shaft 164 is driven from the sprocket gear 92 on the shaft 89 by a chain and sprocket connection 165. As best seen in Figure 9 of the drawings, the lower flight of 20 the sprocket chain 165 is trained under an idler sprocket gear 166.

25 Mounted on one side of the housing 1 is a register 167 which, as best seen in Figures 6 and 9 of the drawings, includes a shaft 168 extending into said housing on which a gear 169 is fixed. The gear 169 is engaged with the segmental gear 97 which is rotatably mounted on the shaft 87 for actuation thereby. A spring latch 170 is engaged with the gear 169 for preventing idle rotation thereof and for facilitating engagement of the slidable segmental gear 97 therewith. The inner end portion of the shaft 168 of the register is journaled in a supporting bracket 171 which extends inwardly from the 30 adjacent side wall of the housing 1.

35 A vertical rocker shaft 172 (see Figures 7 and 36) is journaled in the housing 1 adjacent the disk 91. A curved finger 173 extends from the rocker shaft 172 and is engaged with the inner face of the disk 91 for actuating said rocker shaft in one direction. A spring 174 actuates the rocker shaft 172 in the opposite direction. Projecting from the lower portion of the rocker shaft 172 is an arm 175 having its free end 40 portion loosely engaged in a socket provided therefor in a disk 176 which is rotatably mounted on the bottom 2 of the housing 1. Projecting from the disk 176 is a lug 177 which is 45 operatively engaged with a normally closed safety switch 178 which is interposed in the electric circuit to the motor 3 and the magnet 18. The disk 176 has formed therein a slot 179 in which the finger 124 on the rocker shaft 118 is engaged. Thus, when the disk 91 is shifted 50 inwardly by pressure on the knob 90, the safety switch 178 is opened and the dog 119 and the arm 120 are swung to inoperative position.

55 Referring now to Figures 4 and 7 of the drawings, it will be seen that a signal bell 180 is mounted in the housing 1 adjacent the rear of the dial 158. Mounted for reciprocation on the bottom 2 of the housing 1 is a slide 181 having upstanding end portions. Rigidly secured on one of the upstanding end portions of the slide 70 181 is a rearwardly projecting cam 182 which is slidably engaged in a slot provided therefor in a block 183 which is secured on the bottom 2 of the housing 1. Pivotedly mounted on the block 183 is a hammer 184 which, of course, is 75 adapted to strike the bell 180. The other up-

standing end portion of the slide 181 is positioned in the path of a pin 186 which projects from the cam sleeve 106 for actuating said slide in one direction. A spring 187 returns the slide 181 to its retracted position. Projecting from the pivoted end of the hammer 184 is a finger 188 which rests on the cam 182. It will thus be seen that when the slide 181 is actuated by the pin 186, the cam 182 swings the finger 188 upwardly thereby causing the hammer 184 to 10 strike the bell 180. The mounting of the hammer 184 is such that said hammer swings by gravity away from the bell 180 when the cam 182 is retracted by the spring 187.

15 In Figure 6 of the drawings, the spring drum 126 is shown mounted on a support 189. Projecting forwardly from the support 189 is a lug 190 which is in the path of a stop 191 (see Figure 29) which projects from the cam sleeve 106. The stop 191 is to limit the return rotation of the cam sleeve 106 under impulsion by the spring drum 126.

20 Attention is now invited to Figures 5, 9, 10 and 11 of the drawings wherein the reference numeral 192 designates a coin chute which is pivotally suspended from the casing 30 of the unit 29 for receiving coins from the outlet opening 34 of said casing 30. The lower end of the chute 192 is normally closed by the bottom 2 of the housing 1 but upon being swung inwardly or rearwardly, said chute 192 is brought into communication with an opening 193 in the housing bottom 2. A resilient arm 194 rises from the upper portion of the chute 192 and has its free end portion in the path of the cam 35 45 for swinging said chute inwardly to discharging position against the tension of a return spring 195 which is mounted on the inner side of the casing 30. A stop 196 (see Figure 7) which rises from the housing bottom 2 limits 40 the return movement of the chute 192 under impulsion by the return spring 195.

45 Also depending from the inner or rear side of the casing 30 of the unit 29 is a spring 197 which is inclined rearwardly or away from the 50 chute 192, as best seen in Figure 9 of the drawings. Projecting forwardly from the lower end of the spring 197 is a coin retaining pin 198 which extends slidably through an opening provided therefor in the rear wall of said chute 55 192. It will thus be seen that when the chute 192 is in its forward position the pin 198 is substantially withdrawn therefrom to permit the passage of coins but when the chute 192 is swung rearwardly it is obstructed by the pin 198 which functions to stop any coin which may enter the chute should said chute be manually held in discharging position for any reason. Access to the chute 192 may be had through a window 199 in the front wall of the housing 1. 60 The lower portion of the front wall of the chute 192 has an opening therein through which the coins may be observed, spaced bars 200 traversing said opening.

65 Slidably mounted in the lower portion of the housing 1 for receiving coins from the opening 193 is a drawer 201. As best seen in Figure 9 of the drawings, the bottom 202 of the drawer 201 curves upwardly at one end to provide a front wall 203 which terminates in a downwardly and forwardly curved flange 204 which provides convenient gripping means for opening and closing said drawer. The drawer 201 may be slidably supported in any suitable manner in the housing 1.

In operation, if the fare or admission to be collected by the machine is, for example, 15¢, the dial 158 is rotated until the numeral 15 thereon appears in the window 161. This is accomplished by pressing inwardly on the knob 90 against the tension of the spring 98 which frees the disk 91 from the pin 94 and disengages the segmental gear 97 from the gear 169 of the register 167. This movement also opens the safety switch 178 and swings the dog 119 and the arm 120 to retracted position. The knob 90 is then rotated for rotating the sprocket gear 92 which drives the dial 158 through the endless chain 165, the shaft 164 and the beveled gears 162 and 163.

Rotation of the knob 90 also causes rotation of the shaft 87. When the shaft 87 is thus manually rotated in one direction, the pin 110 engages the pin 111 (see Figure 39) on the gear 102 for rotating said gear, the drum 99 and the ratchet wheel 103 in said one direction. When the shaft 87 is rotated in the opposite direction, thereby moving the pin 110 in a direction away from the pin 111, the spring drum 115 functions to rotate the drum 99, the gear 102 and ratchet wheel 103 in the opposite direction. In this manner, the distance between the pins 111 and 112 is regulated as desired. When the drum 99 is thus rotated the segmental gear 97, which is now free of the register 167, is adjusted relative to the register gear 169. The knob 90 is then released and the spring 98 meshes the segmental gear 97 with the register gear 169, this movement of the gear 97 pushing the shaft 89 and the disk 91 outwardly at which time the pin 94 enters one of the openings 93 in said disk 91 for retaining the adjustment which has been made. When the shaft 87 is manually rotated the spring drum 126 prevents the cam sleeve 106 from rotating with said shaft in one direction and the stop elements 190 and 191 prevent the sleeve 106 from rotating in the opposite direction with said shaft.

Now, if a dime, for example, is inserted in the chamber 31 of the unit 29 through the inlet slot or opening 33, the bar 59 is actuated against the tension of its spring 64 until the shoulder 61 clears the substantially pointed upper end of the plate 50 of the switch 49. After thus retracting the bar 59, the dime drops into the chamber 31 between the follower 35 and the slide 39. The spring 64 then moves the bar 59 forwardly and the shoulder 61 engages the free upper end of the plate 50 and swings said plate 50 forwardly in a manner to engage the contacts 55 and 56, thus closing the electric circuit to the motor 3 and the magnet 18. This forward swinging movement of the plate 50 is against the tension of the spring 58. It may be well to here state that when the shoulder 61 is moved rearwardly beyond the upper end of the plate 50, said plate is elevated by the spring 58 to assure engagement of the shoulder with the plate when the bar 59 is moved forwardly by its spring 64. Attention is also here invited to the fact that when the spring 98 returns the segmental gear 97, the disk 91, etc., to operative position, the spring 174 on the vertical rocker shaft 172 functions to close the safety switch 178 and the spring 123 is permitted to swing the dog 119 and the arm 120 inwardly to operative position.

When the switch 49 is closed the electromagnet 18 is energized and shifts the clutch 9 to engaged position with the pulley 5, thereby

connecting the disk 22 with the electric motor 3. The disk 22 is thus rotated and the follower 35 is moved forwardly in the chamber 31 by the pitman 37. The dime which has been inserted engages one of the steps 40 on the slide 39 and said slide is moved forwardly against the tension of the spring 48 a distance sufficient to bring the segmental gear 79 having two teeth thereon (see Figure 20) into mesh with the gear 102 on the normally stationary shaft 87. When the segmental gear 79 is in mesh with the gear 102 the dog 68 which is fixed on the spring actuated lever 65 drops into one of the openings 44 in the wing 42 of the slide 39 for retaining the gears 79 and 102 in engagement. As hereinbefore stated, the slide 39 is connected to the integral segmental gears 79 to 82, inclusive, through the medium of the finger 43 which is engaged in the annular groove 83 of the segmental gear sleeve 18.

After the gears 79 and 102 are in engagement, the segmental gear 23 on the inner side of the disk 22 engages the segmental gear 25 for rotating the shaft 24 upon which the segmental gear 79 is, of course, splined. It will thus be seen that the gear 102 will be rotated a distance corresponding to the two teeth of the segmental gear 79. The segmental gear 97 is, of course, rotated a distance corresponding to the distance that the gear 102 is moved which will cause the register 167 to record the ten cents which has been inserted in the machine. However, the distance traveled by the gear 102 is not sufficient to engage the pins 111 and 112 and the change return mechanism will, therefore, remain inoperative.

The dime then drops through the opening 34 into the chute 192 and the slide 39 is returned to retracted position by the spring 48. This, of course, returns the segmental gear unit comprising the gears 79 to 82, inclusive, to their former position on the shaft 24, as seen in Figure 6 of the drawings. With each operation the shaft 24 makes one complete revolution but the cam sleeve 18 is returned to its former position just before the revolution is completed to position the cam 86 for engagement with the pin 128 of the dog 127. Thus, as the revolution of the cam sleeve 18 with the shaft 24 is completed, the dog 127 is swung upwardly out of engagement with the ratchet wheel 108 on the cam sleeve 106.

After the dime drops through the opening 34 into the chute 192, the follower 35 is returned to retracted position by the pitman 37. As the follower 35 approaches the end of its return movement or stroke, the pin 36 engages the cam 67 and lifts the lever 65 against the tension of the spring 69 thereby lifting the dog 68 to inoperative position which permits the spring 48 to return the slide 39. After lifting the lever 65, the pin 36 engages and actuates the angular lever 70 for rotating the ratchet wheel 75 through the medium of the pawl 74, said ratchet wheel being moved a distance corresponding to one tooth. The ratchet wheel 75 then functions as a cam, forcing the pin 51 of the plate 50 downwardly, thereby disengaging said plate from the shoulder 61 for permitting the spring 58 to rock the plate 50 in a direction to disengage the contacts 55 and 56 of the switch 49, thereby opening the electric circuit to the motor 3 and the magnet 18. When the magnet 18 is de-energized, the spring 19 disengages the clutch 9 and the segmental gear 22 comes to rest after

having made one complete revolution. The segmental gears 23 and 25 are provided with corresponding numbers of teeth and said gear 25 also comes to rest after having made one complete revolution, the headed pin 27 seating in the concavity provided therefor in the gear 25 to assure that the shaft 24 will stop in such a position that the segmental gears 79 to 82, inclusive, will mesh with the gear 102 without clashing. When the dime drops into the chute 192 it comes to rest on the bottom 2 of the housing 1 in the lower portion of said chute where it may be observed through the window 199 and the opening in the lower portion of said chute.

When the drum 99 with the gear 102 and ratchet wheel 103 is rotated a distance corresponding to the two teeth on the segmental gear 79 upon the insertion of the first coin, the cable 114 is wound on said drum against the tension of the spring drum 115 and said drum is secured against rotation in the opposite direction under impulsion by the spring drum 115 through the medium of the dog 119 which is engaged 25 with said ratchet wheel 103. At this time the projection 121 on the arm 120 is engaged in the recess 122 of the disk or cam 113. Also, when the first coin is inserted as hereinbefore set forth, the pin 111 which projects from the gear 102 is brought to a position substantially 30 in side abutting engagement with the pin 112 on the disk or cam 113.

When the dial 158 was set to bring the numeral 15 thereon before the window 161, the segmental gear 97 was simultaneously adjusted relative to the register gear 169 so that but three teeth of said segmental gear 97 would drive the gear 169, as suggested in Figure 9 of the drawings, each of the teeth on the gear 97 representing a nickel. It will, therefore, be seen that when a dime is inserted in the machine, the gear 97 is moved a distance corresponding to two of its teeth which will leave but one tooth to drive the register gear 169.

Now, if a second dime, for example, is inserted in the machine the segmental gear 29 is again engaged with the gear 102 and said gear 102 is moved a distance corresponding to two more of its teeth. When this occurs the cam sleeve 106 is rotated a corresponding distance through the medium of the pins 111 and 112. When the cam 113 on the sleeve 106 is thus rotated the projection 121 of the arm 120 is forced out of the depression 122 in said cam 113 thereby disengaging the dog 119 from the ratchet wheel 103 which permits the spring drum 115 to return the drum 99 to its former position as soon as the segmental gear 79 has cleared the gear 102. This also returns the segmental gear 97 to its former position but not until after the remaining tooth thereon has actuated the gear 169 for registering an additional five cents on the register 167. The gear 169 ratchets on the shaft of the register 167 so that the register will be actuated when the said gear 169 is rotated in one direction only, thus permitting the segmental gear 97 to be reset as explained.

When the sleeve 106 is rotated a distance corresponding to two of the teeth on the gear 102, the cam shown in Figure 33 of the drawings is moved to bring the first high point thereon into engagement with the adjacent rocker arm 152 for lifting said adjacent rocker arm upwardly in a manner to dispose the shoulder 153 thereon in the path of the cam 85 on the shaft 24. In

this manner one of the levers 151 is rocked to move the plunger rod 155 which is connected thereto forwardly against the tension of its respective spring 157 for shifting the ejector 136 of the nickel containing magazine 133 forwardly 5 to deposit a nickel in the hopper 140. This nickel is removed by sliding the sleeve 142 upwardly thereby swinging the closure 143 of the hopper downwardly to open position.

When the sleeve 106 is rotated for setting the cam or cams 107 the cable 125 is wound thereon against the tension of the spring drum 126. The cams 107 are secured in set position against the tension of the spring drum 126 by the dog 127. Now, when the sleeve 78 bearing the gear 15 segments 79 to 82 is returned to its former position, the cam 85 on said sleeve 78 engages the pin 128 as the sleeve 78 completes its revolution and kicks the dog 127 out of engagement with the ratchet wheel 108 thereby permitting the spring drum 126 to reset the cams 107 which, in turn, permits the springs 157 to return the elements 151, 152 and 155 to their former position. As previously explained, the springs 154 maintain the rocker arms 152 in engagement 25 with the cams 107.

When the slide 39 moves forwardly upon the insertion of the second dime, the cam 45 engages the resilient arm 194 of the chute 192 in a manner to swing said chute inwardly to 30 discharge the first dime into the money drawer 201 through the opening 193. Should the second dime enter the chute 192 before the first dime has been discharged therefrom, said second dime will be arrested by the pin 138. As 35 the slide 39 begins its return stroke, thereby disengaging the cam 45 from the resilient arm 194, the chute 192 is returned to closed position by the spring 195. The second dime is then free to drop to the lower portion of the 40 chute.

When the coin is inserted which brings the total amount which has been paid into the machine by the patron up to or above the correct fare, thereby actuating the cam sleeve 106, 45 the pin 186 is moved away from the adjacent upturned end of the slide 181, thereby permitting the spring 187 to retract the cam 182. Then, when the dog 127 is disengaged by the cam 86 from the ratchet wheel 108, thereby permitting 50 the spring drum 126 to reset the sleeve 106, the pin 186 actuates the slide 181 against the tension of its spring 181 for shifting the cam 182 in a direction to cause the hammer 184 to strike the bell 180 thereby indicating that an amount at 55 least as much as the correct fare has been deposited in the machine.

It is believed that the many advantages of a coin collector constructed in accordance with the present invention will be readily understood and although the preferred embodiment of the invention is as illustrated and described, it is to be understood that changes in the details of construction and in the combination and arrangement of parts may be resorted to which will fall within the scope of the invention as claimed.

What is claimed is:—

1. A coin collector comprising, in combination, a change return mechanism, including a gear, drive means for the change return mechanism, said drive means including a plurality of segmental gears selectively engageable with the first-named gear, and means controlled by the coins which are collected for selectively en- 75

gaging the segmental gears with said first-named gear.

5 2. A coin collector comprising, in combination, a change return mechanism, drive means for said change return mechanism, manually adjustable means for operatively connecting the drive means to the change return mechanism, and means controlled by the coins which are collected for operatively connecting said drive 10 means to the manually adjustable means.

10 3. A coin collector comprising, in combination, a change return mechanism, drive means for said change return mechanism, manually adjustable means for operatively connecting the 15 drive means to the change return mechanism, and means controlled by the coins which are collected for operatively connecting said drive means to the manually adjustable means, said manually adjustable connecting means including a gear, and said drive means comprising a plurality of segmental gears selectively engageable with the first-named gear.

20 4. A coin collector comprising, in combination, a change return mechanism, drive means for said change return mechanism, said drive means including a gear and a plurality of segmental gears selectively engageable with the first-named gear, a shiftable member operatively connected with the segmental gears for selectively engaging said segmental gears with the first-named gear, and coin controlled means for actuating the shiftable member, said coin controlled means being arranged to be operatively connected to the shiftable member by coins inserted therein.

25 5. A coin collector comprising, in combination, a change return mechanism, drive means for said change return mechanism, manually adjustable coupling means operatively connecting the drive means to the change return mechanism, an adjustable indicating dial operatively connected to the manually adjustable coupling for actuation thereby, and means arranged to be controlled by coins inserted therein for operatively connecting the drive means to the adjustable coupling means.

30 6. A coin collector comprising, in combination, a change return mechanism, drive means for said change return mechanism, manually adjustable coupling means operatively connecting the drive means to the change return mechanism, an adjustable indicating dial operatively connected to the manually adjustable coupling for actuation thereby, and means controlled by coins inserted therein for operatively connecting the drive means to the adjustable coupling means, said coupling means including a gear, the drive means comprising a plurality of segmental gears selectively engageable with 35 the first-named gear.

7. A coin collector comprising, in combination, a change return mechanism, drive means for said change return mechanism, manually adjustable coupling means for operatively connecting the drive means to the change return mechanism, said coupling means including a gear, the drive means comprising a plurality of segmental gears selectively engageable with the first named gear, an indicator operatively connected with the adjustable coupling means for actuation thereby, and a register adjustably and operatively connected to the coupling means for actuation thereby. 5 10

8. A coin collector comprising change return mechanism including gear means, a coin register, actuating means for operating both the change return mechanism and the register, said actuating means including second gear means, said second gear means being shiftable relative to the first gear means to position said second gear 20 means to operatively engage selected portions of said first gear means.

9. A coin collector comprising change return mechanism including gear means, a coin register, actuating means for operating both the change 25 return mechanism and the register, said actuating means including second gear means, said second gear means being shiftable relative to the first gear means to position said second gear means to operatively engage selected portions 30 of said first gear means, said first and said second gear means both including sector gears, corresponding ones of which are in non-engaged relation while being shifted and during a part of the relative rotation thereof. 35

10. A coin collector comprising change return mechanism including gear means, a coin register, actuating means for operating both the change return mechanism and the register, said actuating means including second gear means, 40 said second gear means being shiftable relative to the first gear means to position said second gear means to operatively engage selected portions 45 of said first gear means, said actuating means including worm and wheel means for shifting said second gear means relative to said first gear means.

11. A coin collector comprising change return mechanism, a register, actuating means operatively connected to said change return mechanism and said register, said change return mechanism comprising first gears, said actuating means comprising second gears, and coin controlled means operative according to the coins 50 collected to selectively engage operatively respective different ones of said second gears with corresponding ones of said first gears. 55
